W. D. Shoemaker
Inventor;

UNITED STATES PATENT OFFICE.

WILLIAM D. SHOEMAKER, OF DRUMMOND, MARYLAND.

LOOSE-LEAF FILE OR BINDER.

1,385,590.

Specification of Letters Patent. Patented July 26, 1921.

Application filed November 17, 1919. Serial No. 338,684.

To all whom it may concern:

Be it known that I, WILLIAM D. SHOEMAKER, a citizen of the United States, residing at Drummond, in the county of Montgomery and State of Maryland, have invented certain new and useful Improvements in Loose-Leaf Files or Binders, of which the following is a specification.

This invention relates to loose leaf files or binders, and more particularly to such a file or binder intended to loosely hold data sheets between firmly held separator sheets, the separator sheets bearing indicia in convenient position along their edges to identify the data sheets held between them, to the end that the latter may be replaced when removed for any reason.

The specific adaptation of the file or binder is for holding "soft copies" of United States and foreign patents. In the patent departments of manufacturing concerns, where special patent libraries are maintained, binders are employed for conveniently assembling copies of patents in desired compilations. These binders must permit the ready removal of the copy of the patent and also indicate to a subsequent searcher that the copy has been removed, and to the filing clerk the proper place to which it should be returned. To this end the number of the patent to occupy a particular space in the file or binder is placed upon the margin of the associated separator sheet. To make the absence of a copy conspicuous, a distinctively colored separator sheet is employed.

The file or binder which I have devised for this purpose consists primarily of covers and separator sheets between them, fastening means being provided for connecting the covers and separator sheets, preferably in clamped relation, the separator sheets being connected together in series.

Among the objects accomplished by my invention may be mentioned the ease of assembling, the proper spacing of the separator sheets and their reinforcement at points adjacent the fastening means and the convenience in adding or subtracting separator sheets.

In the drawings,

Figure 1 is an end elevation of the file or binder,

Fig. 2 is a perspective of one end of the fluted member employed as a connector for the separator sheets,

Fig. 3 is a perspective of a unit, comprising six separator sheets and the fluted connector, the unit being spread out,

Fig. 4 is an edge view of parts of two such units, showing the manner in which they may be connected to form a larger unit,

Fig. 5 is an edge view of a portion of such a unit, illustrating the manner in which an additional separator sheet may be inserted,

Fig. 6 is a view similar to Fig. 5 showing a modified form, and Figs. 7, 8 and 9 are views similar to Fig. 1 showing my improved file unit used with other forms of cover members and fastening means.

Like reference characters will refer to similar parts throughout the several figures of the drawings.

The form of the invention shown in Figs. 1 to 5 will be first described in detail, after which the modifications shown in Figs. 6 to 9 will be understood from a brief reference thereto.

Covers A, B, comprising a clamping or brace section *a* and a hinged section *b*, are connected by a common form of post and screw fastener C, known as the Chicago fastener, and consisting of a main or post member *c'*, shown in Fig. 1 as broken, and a screw *d*. The post and screw are provided with heads *c*, the usual groove being provided in the screw head for manipulation in the well known manner. Eyelets are provided in the clamping or brace sections of the covers to receive the post and screw, but to retain the heads.

The particular form of fastener, however, is of relatively small importance, as many of the common fasteners now on the market may be used as an element of my invention, including the simple spring clasp shown in Fig. 7.

In Fig. 3 is shown a separator or file unit F, comprising a series of separator sheets *f* connected together by a fluted strip G, best shown *per se* in Fig. 2. There are six sheets so connected in this unit, this number of sheets having been selected as a convenient number to be perforated at a single punching operation. The fluted strip may be of a width to conveniently cover well one hole or perforation *i*, in which case, two or more strips will be required to form the unit; its width may be slightly in excess of the distance between the upper and lower perforations; or it may be the full width of the separator sheet.

The separator sheets may be attached to the strip G either before it is fluted, or afterward, but in any event the separator sheets are attached by paste, glue or otherwise to one side of the flute, as may best be seen in Fig. 4, wherein f represents the separator sheets, G the fluted strip as a whole, while g' and g^2 , respectively, the attached and the free sections of the flute.

When a fastener of the general type of the Chicago screw post is used, holes of a size to conveniently accommodate the parts thereof are punched through the separator sheets and both the attached and free sections of the fluted strip, so that when the fluted strip is collapsed, as shown in Fig. 1, the perforations will be in perfect alignment. This punching may be done prior to the connection of the separator sheets and the fluted strip, or thereafter. If done prior thereto, the unit F may contain a larger number of sheets; in fact as many sheets as may be required in the finished file or binder. The same result, however, may be obtained by connecting units of six sheets by pasting or otherwise, as suggested at m in Fig. 4.

It will be apparent that the portion g' of the fluted strip when attached by adhesive to the separator sheets at the point where they are punched provides an efficient reinforce for that portion of the separator sheet, and that the two portions g' and g^2 together with the film of adhesive, when used, constitutes a spacing member between adjacent sheets, when the unit is collapsed, to compensate for the thickness of the data sheet or sheets normally between the separator sheets.

Referring now to Figs. 3 and 4, attention is directed to the spread or open position of the file unit F, in which position the separator sheets lie upon one another in overlapped condition, the overlap being uniform, leaving a space at the edge of each separator sheet for the placing of indicia, for instance, the number of a patent, when the file is to be used for the keeping of copies of patents, to the end that the absence of a particular patent may be readily noted by a subsequent searcher, and replaced in its proper place by the filing clerk. The unit in this spread-out condition is also used for assembling the patents or data sheets within the file or binder, as the overlapping portions with the indicia thereon form a convenient means of selecting the proper leaf to be raised in order that the patent or data sheet may be placed thereunder. It will be understood that the patents are unstapled and the drawings turned over, to the end that they may be viewed upon a turning of the separator sheets in the finished file or binder. After the data sheets or patents have been placed between the

separator sheets, the unit may be collapsed and in such condition placed upon the post or other fastener.

After the unit or units have been placed upon the post, the cover A is brought into position so that the screw member may be inserted in the eyelet thereof and screwed into the upper end of the post member, which is provided with interior screw threads for that purpose, thus firmly connecting, and preferably clamping, the several parts together, it being understood that these fasteners may be supplied in several lengths to accommodate the thickness of the particular file unit used.

If the fluted strip has not provided sufficient spacing capacity, additional spacing members, preferably of a width and length to fit within a flute member, may be inserted between free sections of flutes and separator sheets, as shown at n in Fig. 4, or between units, as shown at n in Fig. 1.

If after assemblage, it should be desired to insert at any point an additional separator sheet, as when an additional patent of an early date has been found belonging to the selected group of patents, it may be easily done by unfastening the binder and removing from the posts sufficient units to enable said sheet to be placed between the proper separator sheet and the adjacent free section of a flute, as best seen in Fig. 5 at P, the forming of a flute with one attached and one free section making this possible.

In the form of the invention shown in Fig. 6, no fluted strip separate from the separator sheets is used, but instead the equivalent is provided by making a flute upon the edge of each separator sheet, which flute as a whole is designated by the character s, while s' and s^2 represent, respectively, the free and attached sections thereof. The attached section s^2 of the flute on one separator sheet provides the means of connection with the adjacent separator sheet to form the unit F'.

Instead of adhesive, connection between flute sections and separator sheets may be made by stapling or by stitching, and particularly in the form of the invention shown in Fig. 7, where the binder is provided with a spring back T, and hinged covers T' and T², the separator units being clamped between the portions t, t, of the spring back. In this form, the stitching or staples form additional spacing means.

Figs. 8 and 9 represent two other well known forms of commercial binder covers, in connection with which I have chosen to illustrate my invention. The binder of Fig. 8 is known as the "wing" binder in which the brace member u of the cover is connected to the hinge member u² at u³, whereby the heads of the post and screw are hidden from view when the binder is closed,

and the desk or table upon which the binder may be placed is protected from any scratching by means of the heads. The form of the invention shown in Fig. 9 is provided with a back made in two sections v and v^2 , which will slide upon each other in the clamping operation of the binder. These back sections are formed with the brace sections v' and a sheet metal plate or reinforce of angle formation v^4 is provided. The post and screw of this binder is capable of greater expansion than the one shown in Fig. 1. The position shown is that of maximum expansion with the edges of the back sections approximately abutting as shown at v^3 ; in its position of minimum expansion, the back sections will overlap, and they are made springy so that they will rub or closely engage each other.

20 What I claim is:

1. In a file or binder, the combination of cover members, fastening means for connecting the same, and a file unit held by said fastening means between said cover members and comprising a plurality of separator sheets and means for holding said sheets in a pile in a collapsed condition of the unit or in a fixed relationship with each other in a spread out condition of the unit.
2. In a file or binder, the combination of cover members, fastening means for connecting the same, and a file unit held by said fastening means between said covers comprising a plurality of separator sheets

and a connector for said sheets in the form 35 of a plurality of flutes, one section of each flute being free and the other attached to a separator sheet.

3. In a file or binder, the combination of cover members, a file unit held between said 40 cover members and comprising a plurality of separator sheets and a connector for said sheets in the form of a plurality of flutes, one section of each flute being free and the other attached to a separator sheet, said 45 sheets and flutes being provided with aligned perforations, and fastening means passing through said perforations and connecting said covers and file unit.

4. In a file or binder, the combination of 50 a plurality of separator sheets, a connector for said sheets comprising a plurality of flutes, one section of each flute being free and the other attached to a separator sheet, said flutes and sheets being provided with 55 aligned apertures, and fastening means passing through said apertures to maintain said sheets in a fixed relationship to each other.

5. A file unit comprising a plurality of separator sheets, and connecting members 60 therefor in the form of fluted extensions upon said sheets, one section of the fluted extension being attached to the adjacent separator sheet.

In testimony whereof I hereto affix my 65 signature.

WM. D. SHOEMAKER.
